(57) **CLAIM**

The ornamental design for a headset earphone assembly, as shown and described.

DESCRIPTION

FIG. 1 is a perspective view of a headset earphone assembly showing my new design.

FIG. 2 is a left side elevational view thereof;

FIG. 3 is a right side elevational view thereof;

FIG. 4 is a rear elevational view thereof; and,

FIG. 5 is a front elevational view thereof.

All parts of the figures shown in dashed line are not part of the claimed design.
